(57) **CLAIM**

The ornamental design for a price channel gripper flag sign holder, as shown and described.

DESCRIPTION

FIG. 1 is a perspective view showing the price channel gripper flag sign holder in an environment of use, mounted in a price channel of a shelf and holding a sign;
 FIG. 2 is a perspective view taken from the front, top, left side of the price channel gripper flag sign holder;
 FIG. 3 is a front elevational view thereof;
 FIG. 4 is a back elevational view thereof;
 FIG. 5 is a elevational view of the right side thereof;
 FIG. 6 is an elevational view of the left side thereof;
 FIG. 7 is a top plan view thereof;
 FIG. 8 is a bottom plan view thereof; and,
 FIG. 9 is an exploded perspective view taken from the bottom, front, right side thereof.
 The broken line showing of the price channel, shelf, and sign is for the purpose of illustrating environmental structure and forms no part of the claimed design.

1 Claim, 4 Drawing Sheets
